UNITED STATES PATENT OFFICE

WILLIAM A. UTTZ, SR., OF ST. LOUIS, MISSOURI

PACKAGE-SEALING MACHINE

Application filed January 23, 1928. Serial No. 248,931.

My invention relates to package sealing machines and more particularly to package sealing machines which will moisten the sealing paper or gummed paper entirely to both ends of the sealing paper section; and the object is to provide simple machines which are highly efficient for cutting and moistening gummed service paper for sealing packages and which can be manufactured and installed at relatively small cost. Other objects and advantages will be fully explained in the following description and the invention will be more particularly pointed out in the claims.

Reference is had to the accompanying drawings which form a part of this application.

Figure 1 is a side elevation partly in section of one form of the invention.

Figure 2 is a plan view of one modification thereof.

Figure 3 is a perspective view of a slightly modified form of cover plate adapted to be used in the constructions shown in Figures 1 and 2.

Figure 4 is a perspective detail of a certain roll support adapted to be used herewith, the view being partly in section and partly broken away.

Figure 5 is a perspective view of a second modification of the invention, similar to Figure 1 but provided with a roll cover.

Figure 6 is a detail perspective of part of the device as shown in Figure 5 but with the roll cover raised.

Figure 7 is a detail perspective of a moistener used herewith.

Similar characters of reference are used to indicate the same parts throughout the several views.

This machine has a one piece body but there are two compartments. Compartment 1 is the paper roll container and compartment 2 is the compartment for serving the paper. The bottom of the compartment 1 is concave and

may be perforated with slots. The object is to provide a bottom on which the roll of paper will automatically adjust itself to the lowest point in the compartment. A wedge 3 is placed in the compartment 1 in front of the paper roll 5 and this weight will follow the paper roll downwardly as the paper roll becomes smaller. In this manner the paper roll will not move so far when a section of paper is drawn forward to be cut off. An adjustable paper roll holder is provided and placed inside of the compartment 1 and consists of two parts 6 and 7. This arrangement is best shown in Figure 4 wherein it will be seen that the parts 6 and 7 are of the general form of arcuate angles having overlapping legs 6a and 7a, these legs being rabbed as shown. One leg, as 7a, is provided with transverse slots 7b through which pass suitable screws as 6b so that the two members when assembled form an arcuate channel adjustable for width and adapted to be secured in adjustment by said screws. The parts 6 and 7 are movable towards and from each other while their bottom members slide against each other. After the parts 6 and 7 are adjusted, they may be made rigid with each other. The object is to provide a holder which is adjustable to different widths of paper. The compartment 1 is provided with a hinged cover 8 for the paper roll 5 and this cover carries the cutter 9 which is a part of the paper feeding mechanism.

The compartment 2 contains a supply of water for moistening the paper and the cover 11 for the compartment forms a part of the feeding mechanism. In the form shown in Figs. 1, 2, and 3, the cutter 9 and the feeding plate 11 are secured to the compartment 2 by bolts 12 and lugs 13 and the cutter 9 is pivotally connected to the compartment by bolt 12 and has its swinging front end releasably latched down to cover the compartment 2 by latches 14 which engage lugs 13. A small compartment 16 is formed in the compartment 1.

ment 2 for the moistener brush 15 by means of a partition 17 which has perforations 18 so that water can pass from the larger compartment 2 into the brush compartment or holder 16. Means are provided for holding the brush 15 against the end of the cutting devices 9. A flat perforated plate 19 is provided to stand up against the moistening brush 15 and a spring plate 20 is attached to the brush 15 and plate 19. These three elements 15, 19, and 20 are attached together as a removable unit. The spring plate 20 bears against the end of the compartment 2 and holds the plate 19 against the brush and plate 19 holds the brush against the end of the feeding members. Perforations in the plate 19 permit a better flow of water to the brush.

If the paper is to be fed forward manually the form shown in Figure 3 is used wherein the plate 11 has a slot 21 therein so that the finger will have a better bearing to pull forward on the paper, the tip of the finger pressing the central portion of the strip down into said slot and thereby giving a better area of contact between the finger and strip.

Fig. 1 shows a different means for feeding the paper forward. A roller 22 is journaled in bearings 28 which are attached to the cutter 9. The bearings 28 have elongated openings 24 so that the roller 22 can be elevated slightly for adjusting purposes. The roller is provided with a rubber band periphery 25 to make the roller more effective in feeding the paper forward. The roller 22 can be elevated slightly so that paper can be inserted thereunder. Thereafter the roller 22 rests by gravity on the paper. The roller 22 is moved manually to feed the paper forward. The paper is moved forwardly with the gummed side down. The paper will be drawn past and against the moistening brush 15 and when the strip of paper strip is of sufficient length, it will be drawn against the cutting edge of the cutter for detaching the paper strip. When this form of feeding device is used, the plate 11 will be solid without a slot 21. Friction of the roller 22 will cause the paper to move.

Another form of feeding device is shown in Fig. 2. A bar 26 is pivotally mounted on the cutter and provided with an upstanding tab 27 for convenience in grasping the bar to move the paper. The bar 26 is yielding and may be pressed down on the paper hard enough for the friction against the paper to move the paper. After an operation of feeding a strip of paper forward, a spring 28 will bring the feeding bar 26 back to normal or starting position.

Means are provided for preventing the machine from moving backwardly on a table or counter. The cutting of the strip of paper has a tendency to cause the machine to move

backwardly. In order to prevent this moving of the machine, supporting bars 29 are pivotally connected to the bottom of the machine and at each end, each bar has cavities to receive rubber feet or supports 30. The rubber supports or feet will be yielding so that they will yield slightly backwardly but they will not slip on the table or counter and the elasticity of the rubber will bring the machine back to the required position. The supporting bars 29 serve to prevent the machine from turning over because they substantially extend the base. The bars 29 can be turned longitudinally of the machine for packing and shipping purposes.

One advantage of making the cover 9 integral with the cover 8 is that the cover 9 and the plate 8 may be raised as a unit so that the paper strip may be simply laid on the plate 11. Thus the placing of the strip in position for operation is easily accomplished and threading is eliminated. The cover 9 is made stationary when brought to operative position by latches 14 and lugs 13. This is necessary for the successful operation of cutting the paper.

Various changes in the sizes, proportions, construction and arrangement of the several parts of this machine may be made without departing from my invention.

What I claim is,

1. A package sealing machine comprising a compartment for containing a paper roll and a compartment for serving paper communicating with the first mentioned compartment, means associated with said serving compartment for guiding and cutting the paper and consisting of a bearing plate mounted on said serving compartment, a cover for said paper roll compartment, and a plate carried thereby and adapted to lie in close proximity to said bearing plate and provided with a slot therein for insertion of a moving means and provided with a cutting edge, and means projecting through said slot for engaging and moving the paper.

2. A package sealing machine comprising a compartment for containing a paper roll and a compartment or unit for serving paper, said last compartment having communication with the first compartment, a bearing plate mounted on said serving compartment for supporting paper received from said paper roll compartment, and a hinged cover for said paper roll compartment carrying a guide and cutting plate integral therewith and arranged to be brought in close proximity to said bearing plate after the paper has been placed on said bearing plate.

3. A package sealing machine comprising a compartment for containing paper rolls and a compartment or unit for serving paper, said last compartment having communication with the first compartment, a bearing plate mounted on said serving compartment

for supporting paper received from said paper roll compartment, a hinged cover for said paper roll compartment carrying a guide and cutting plate integral therewith and arranged to be brought in close proximity to said bearing plate after the paper has been drawn forward and placed on said bearing plate, means on said plate for feeding the paper, and means for latching said guide and cutting plate to the serving compartment.

10 In testimony whereof, I set my hand, this 5th day of January, 1928.
